UNITED STATES PATENT OFFICE.

IRVING W. DILLON, OF LAWRENCE, MASSACHUSETTS.

CARBURETER.

1,209,405.

Specification of Letters Patent. Patented Dec. 19, 1916.

Application filed December 14, 1915. Serial No. 66,804.

To all whom it may concern:

Be it known that I, IRVING W. DILLON, a citizen of the United States, residing at Lawrence, in the county of Essex and State of Massachusetts, have invented certain new and useful Improvements in Carbureters; and I do hereby declare the following to be a full, clear, and exact description of the invention, such as will enable others skilled in the art to which it appertains to make and use the same.

This invention relates to carbureters of that type especially designed for use in connection with internal combustion engines, and has for its primary object to provide an improved and simplified carbureter embodying means whereby the relative proportion of gasoline and air may be varied so as to insure maximum working efficiency of various types of internal combustion engines.

Another object is the provision of means controlled by the throttle lever for admitting an auxiliary supply of air to the intake pipe of the engine when the latter is running at high speed or the throttle is opened to a predetermined point.

Another object is the provision of a carbureter embodying a mixing chamber having a plurality of air inlet ports formed in the wall thereof at a point adjacent the needle valve, thereby insuring a more thorough carburetion of the liquid fuel.

With these and other objects in view the invention consists in the novel construction, arrangement and formation of parts as will be hereinafter specifically described, claimed and illustrated in the accompanying drawings, in which:

Figure 1 represents a longitudinal sectional view through the improved carbureter, partly in side elevation. Fig. 2 represents a plan view of the carbureter, Fig. 3 represents a transverse sectional view in the plane of the float chamber, partly in end elevation, Fig. 4 represents a detail sectional view through the needle valve stem. Fig. 5 represents a detail sectional view through the adjusting track for the needle valve.

Referring to the drawing in detail, where in similar reference numerals designate corresponding parts throughout the several views, the numeral 8 indicates the body of the carbureter, which is preferably of substantially cylindrical formation and provided at one end with a head 9 adapted for connection with the intake pipe of an inter-

nal combustion engine (not shown). The end of the body 8 opposite the head or coupling 9 is formed with an air intake port 10 and the interior 11 of said body constitutes the mixing chamber of the carbureter. The central portion of the body 8 is formed with a plurality of spaced and relatively small free air intake ports 8^a. An air valve 10^b is arranged in the intake port 10 and is normally retained closed by the tension of a spring 10^c, the tension of which may be varied as desired by an adjusting screw 10^d.

The bottom of the body 8 is formed with a depending hollow extension 12 formed at its opposite sides with fuel ports 12^b. A horizontally disposed fuel pipe 12^c is formed at one end with an annular member 12^e rotatably mounted upon the hollow extension 12 and adapted to be secured in adjusted position by a flanged plug or cap 12^d. The horizontally disposed fuel pipe 12^c may be adjusted so as to project laterally of either side of the carbureter body 8 and thus permit the float chamber 13 to be arranged on either side of the carbureter body, as desired. In either adjusted position the bore of the horizontal fuel pipe 12^c registers with one or the other of the fuel ports 12^b in the depending extension 12 and the opposite end of the bore of said fuel pipe communicates by a passage 12^a with a float chamber 13, in which is arranged a float 16, having a laterally projecting arm 17 pivotally secured at 18 in the valve housing 18^a formed integral with the wall of the chamber 13. The upper open end of the float chamber 13 is preferably closed by a removable top plate 14, which latter is normally retained in closed position by the tension of a pivoted leaf spring 15, and the outer free end of the float carried arm 17 is connected with a needle valve 19 adapted to control the flow of liquid fuel through the fuel inlet port 20 formed in the bottom of the valve casing 18 and adapted to be connected with a fuel pipe (not shown).

The lower central portion of the carbureter body 8 is formed with a port in which is secured a sprayer nozzle 21, having the upper end of the bore thereof flared and adapted to cooperate with the pointed end of a needle valve 22 slidably mounted in an aperture 24 formed in the upper portion of the body 8 and having a head or handle 25 at its upper exposed end. The upper exposed portion of the stem of the valve 22 is formed with external screw threads upon which is

fitted a nut 26, having diametrically opposed peripheral grooves slidably receiving the bifurcated ends 27 of a support 28, which latter is pivotally secured by a pin 29 extended through the bifurcations 27 and mounted in a pair of uprights 30 formed integral with the upper portion of the carburetor body 8. A U-shaped guide 31 is secured at its free ends to the upper portion 10 of the body 8 upon opposite sides of the stem of the needle valve 22 and is formed in its web portion with an aperture receiving the upper extremity of the valve for guiding the vertical movement thereof. An expansion spring 32 is coiled about the stem of the needle valve and is engaged between the web portion of the U-shaped guide 31 and the nut 26, for normally retaining the needle valve in downwardly extended position.

20 The free end of the supporting arm 28 is formed with a socket 34 in which is rotatably mounted a bearing ball 35 engaged with a curved flexible track or strip 36 adjustably secured at its opposite ends by 25 screws or equivalent means 37 to a segmental plate 38 rigidly secured to or formed integral with the throttle arm 39, which latter is nonrotatably secured to a stem or shaft 40 rotatably mounted in diametrically opposed apertures formed in the body 8 and carrying the throttle valve 42 adapted to control the passage of gaseous fuel through 30 the body 8.

35 The central portion of the flexible track or strip 36 is supported upon screws 43 threaded into apertures formed in the plate 38 and provided with heads whereby they may be conveniently adjusted to raise or lower the track. The track is secured to the headed 40 ends of the adjusting screws 43 by relatively small screws 44.

45 Adjacent its discharge end, the body 8 is formed with a plurality of radial auxiliary air ports 46 formed inwardly of the flange or head 9 and through which the flow of auxiliary air is controlled by the rotatable collar 47 formed with a plurality of ports 48 adapted to be moved into registration with the ports 46 in the body 8. The collar or 50 sleeve 47 is formed with a pair of spaced parallel arms 50, one of which is formed with an internally screw threaded aperture receiving an adjusting screw 51 engaged with the upper surface of the relatively 55 short arm of a bell crank 52, which latter is pivotally secured to a pin 53 projecting laterally of the body 8 inwardly of the apertures 46. A spring 53^a is engaged between the other arm 50 and the relatively short 60 arm of the bell crank 52 and normally retains the latter in engagement with the adjusting screw 51. The long arm of the bell crank 52 is formed in its free end with a socket 54 receiving the spherical end of an 65 adjustable link 55, which latter is secured

at its opposite end to a lateral projection 56 of the segmental plate 38.

In use, the quantity of liquid fuel entering the mixing chamber 11 through the nozzle 21 is properly regulated by adjusting 70 the needle valve 22 in the nut 26 and when the throttle is opened the pivoted arm 28 is lifted upon the inclined track or strip 36, thus simultaneously opening the needle valve 22. The extent of movement of the needle valve 22 under the influence of the track or strip 36 may be varied, as desired, by adjusting the screws 43 and thereby varying the inclination of the track 36. During the opening movement of the throttle valve 42 75 rotary motion is imparted to the sleeve 47 through the link 55 and bell crank 52, and thus when the throttle valve has been opened to a predetermined point the ports 48 in the sleeve are moved into registration with the 80 ports 46 in the carburetor body 8, thus admitting an auxiliary supply of free air to enter the body. The movement of the sleeve 47 with relation to the throttle valve may be varied, as desired, by properly adjusting the 85 screw 51.

What I claim is:

1. In a carburetor, a body having a plurality of auxiliary air ports formed therein, a sleeve rotatably mounted upon said body having a plurality of air ports therein adapted to be moved into registration with the first-mentioned air ports, a pair of spaced laterally projecting arms carried by said sleeve, a bell crank pivotally secured to said body having one of the arms thereof engaged between the first-mentioned arms, an adjustable stop carried by one of the first-mentioned arms engaged by the arm of said bell crank, means normally retaining the arm of said bell crank in engagement with the said adjustable stop, a throttle valve rotatably mounted in said body, and a connection between said throttle valve and said bell crank.

2. In a carburetor, a body having an internal mixing chamber and a plurality of air ports formed therein, a nozzle arranged within said body adjacent said air intake ports, a needle valve associated with said nozzle, a nut adjustably fitted upon said valve and having a pair of diametrically opposed grooves therein, an arm pivotally secured to said body and having one end bifurcated and engaged in the grooves in 120 said nut, a throttle valve rotatably mounted in said body, a segmental plate carried by said throttle valve, a flexible track secured to the surface of said segmental plate, means for adjusting said strip, said strip constituting an adjustable support for the free end of said arm, said body having a plurality of auxiliary air ports therein, a rotatable sleeve engaged with said body having a plurality of apertures therein adapted to be moved 125

into registration with said auxiliary air ports, and means connecting said throttle valve with said sleeve.

3. In a carbureter, a body having an internal mixing chamber and a plurality of auxiliary air ports formed therein, a nozzle arranged in said body, a needle valve associated with said nozzle, an arm pivotally secured to said body and engaged with said 10 needle valve, a sleeve rotatably mounted upon said body having a plurality of air ports therein adapted to be moved into registration with the first mentioned air ports, a pair of spaced laterally projecting arms carried by said sleeve, a bell crank pivotally secured to said body having one of the arms thereof engaged between the first-mentioned 15

arms, an adjustable stop carried by one of the first-mentioned arms engaged by the arm of the bell crank, means normally retaining 20 the arm of said bell crank in engagement with said adjustable stop, a throttle valve rotatably mounted in said body, a connection between said throttle valve and said bell crank, and adjustable means carried by said 25 connection and engaged with said arm for adjusting said needle valve simultaneously with said throttle valve.

In testimony whereof I affix my signature in presence of two witnesses.

IRVING W. DILLON.
